UNITED STATES PATENT OFFICE

2,420,598

LIQUID FUEL BURNER

James H. Jackson, Detroit, Mich.

Application October 4, 1945, Serial No. 620,336

10 Claims. (Cl. 158—28)

1

This invention relates to liquid fuel burning apparatus, and in particular to fuel oil burners.

One object of this invention is to provide a liquid fuel burner having an improved arrangement of air ducts whereby a superior distribution of the air is brought about, thereby bringing about better combustion.

Another object is to provide a liquid fuel burner having a single air conduit divided into two ducts by a longitudinal vane or partition so arranged as to admit air on opposite sides of the air mixing chamber and thereby bring about improved air distribution and superior combustion.

Another object is to provide a liquid fuel burner as set forth in the preceding objects wherein the intake end of the air conduit is substantially aligned with the fuel spray nozzle, thereby facilitating installation and mounting.

Another object is to provide a liquid fuel burner having an improved hearth or retort wherein a flat zone is provided centrally thereof so that the air emerging from the blast ring or central aperture is permitted to move outwardly for a short distance prior to encountering the more strongly curved side walls of the retort, thereby giving improved combustion and providing a layer of air between the inner walls of the retort and the fuel spray so as to maintain the lower portion of the hearth relatively cool and permit the use of a metallic hearth or retort.

Another object is to provide a liquid fuel burner with a bowl-shaped hearth or retort having an annular flange surrounding it near the top thereof, thereby strengthening the retort and serving as a girdle to protect it against cracking due to rapid expansion under rapidly rising temperatures.

Another object is to provide a liquid fuel burner having a bowl-shaped hearth or retort preferably of metallic material, and having an insulating coating on the outside thereof so as to prevent undue loss of heat by conduction and radiation through the retort.

Another object is to provide an improved air supply device for fuel burners consisting of a single air supply conduit curving around the air mixing chamber and divided into two ducts by a longitudinal vane or partition so arranged as to admit air on opposite sides of the air-mixing

2

chamber and thereby bring about improved air distribution and superior combustion.

Another object is to provide a fuel burner having an improved auxiliary air tube associated with the fuel supply nozzle and having improved means for adjusting the flow of air therethrough.

Other objects and advantages will become apparent during the course of the following description of the accompanying drawings, wherein:

Figure 1 is a top plan view of a liquid fuel burner according to the preferred form of the invention, with the top partially broken away to disclose portions of the interior;

Figure 2 is a longitudinal section through the liquid fuel burner of Figure 1, taken along the broken line 2—2 therein;

Figure 3 is a cross-section through the air-mixing chamber taken along the line 3—3 in Figure 1;

Figure 4 is a cross-section through the air intake conduit, taken along the line 4—4 in Figure 2;

Figure 5 is a cross-section through the auxiliary air tube taken along the line 5—5 in Figure 2; and

Figure 6 is a top plan view of a modified form of liquid fuel burner with the top partially broken away to disclose a portion of the interior.

Referring to the drawings in detail, Figure 1 shows a preferred form of the liquid fuel burner of this invention as including a casing 10 having an air supply conduit 11 with an intake portion 12 whose axis is substantially aligned with a liquid fuel spray nozzle 13. The air supply conduit 11 is provided with a central vane or partition 14 (Figure 4) dividing it into two ducts 15 and 16. The end of the partition 14 terminates in an inwardly bent portion 17 serving as an inwardly-directed baffle and curved to prevent direct collision between the air stream entering the air-mixing chamber 18 through the duct 16 and the air stream entering through the duct 15, and bring about a smooth blending thereof. The bent portion 17 also provides a full width of the air duct 15 at its discharge opening 19 and prevents constriction thereof. The casing 10 is provided with a partition 20 forming in effect a continuation of the wall 21 of the conduit 11 and having a bent portion 22 serving as an inwardly-

directed baffle in a manner similar to the bent portion 17 on the end of the partition 14. The bent portion 22 likewise serves to prevent direct collision between the airstreams and brings about a smooth blending thereof. The intake end 12 of the conduit 11 is provided with an internal rib 23 to serve as an abutment for a pipe telescoped into the vestibule 24 thereof and conveying air from the blower of the power plant (not shown). The intake portion 12 is also provided with dampers 25 and 26 within the ducts 15 and 16 and secured to bolts 27 and 28 respectively. The bolts 27 and 28 are provided with spiral springs 29 for urging the dampers 25 and 26 toward their open positions. Adjusting thumb screws 30 and 31 for the dampers 25 and 26 are threaded through the side walls of the casing 11 (Figure 1), and engage the dampers 25 and 26 respectively. By turning the thumb screws 30 and 31 inwardly, the dampers 25 and 26 are caused to move in directions tending to close the ducts 15 and 16, and this adjustment can be fixed by means of lock nuts 32. By adjusting the thumb screws 30 and 31, and consequently the dampers 25 and 26, the air entering the vestibule 24 is proportioned between the ducts 15 and 16 in any desired amount, thereby controlling the relative amounts of air entering the air mixing chamber 18 through the discharge openings 19 and 33 of the ducts 15 and 16 respectively, and the air-mixing chamber 18 is thereby supplied with streams of air from diametrically opposite locations.

The fuel spray nozzle 13 is mounted substantially centrally in the air-mixing chamber 18 and has a spray head 34 threaded into the upper end of a fuel supply stem 35, the lower end of which (Figure 3) is threaded as at 36 and passed through a bore 37 in the bottom wall 38 of the casing 10. Nuts 39 and 40 secured on opposite sides of the bottom wall 38 hold the stem 35 rigidly in position. The stem 35 at its lower end is internally threaded to receive the threaded end 41 of an elbow 42 having a threaded union 43 connecting it to a liquid fuel supply pipe 44 (Figure 2). Surrounding the stem 35 and spaced from it by the spider-like centering member 45 (Figure 1) is an auxiliary air tube 46 having its upper end immediately below the level of the spray head 34 and its lower end resting upon the bottom wall 38. The lower portion of the auxiliary air tube 46 is provided with ports 47 distributed around the periphery thereof and cooperating with an air adjusting sleeve 48 having similar ports 49 therein. A set screw 50 threaded into a boss 51 on the air adjusting sleeve 48 provides for an adjustment of the air passing through the cooperating ports 47 and 49. The sleeve 48, when rotated to a position where the air passages provided by the cooperating ports 47 and 49 are of suitable width, is locked in position by tightening the set screw 50.

The bottom wall 38 is provided with bosses 52 on opposite sides of the bore 37, these being internally threaded as at 53 to receive the threaded ends 54 of ignition plugs 55 having insulators 56 and terminals 57 attached to central electrodes 58 passing into the air mixing chamber 18 through insulating tubes 59. The electrodes 58 are bent at right angles so that their ends 60 form a spark gap (Figure 1). To the terminals 57 are connected wire cables 61 which pass through insulating tubes 62 (Figure 2) mounted in bores 63 in a downwardly extending bracket 64 forming a part of the casing 10. The latter

is supported upon leveling studs 65 (Figures 2 and 4) threaded into the bores 66 in the casing 10 and secured thereto by the lock nuts 67. Threaded upon the lower ends of the studs 65 are conical supports 68 locked in position by the lock nuts 69. The supports 68 may thus be moved upwardly or downwardly upon the studs 65 to level the apparatus and to adjust it to irregularities in the floor, grates or other portion of the furnace upon which the device rests.

The top of the casing 10 is provided with a conical flange 70 providing a circular outlet 71 around the spray nozzle 13. Resting upon the flange 70 is a conical adapter ring 72 having a stepped portion 73 of approximately the same thickness as the flange 70 so that the inner surfaces of the flange 70 and the adapter 72 form a substantially continuous cone. Resting upon the upper annular shoulder 74 of the adapter 72 is a bowl-shaped hearth or retort 75 having a relatively flat or shallowly curved annular zone 76 extending approximately to the boundary circle 77 from the edge circle 78 of the aperture in the center of the hearth 75. Beyond the boundary circle 77 of the flat zone 76, the hearth 75 is provided with a more strongly curved side wall 79.

The hearth 75 near its upper edge 80 is provided with an integral annular flange 81. The latter serves as a strengthening member or girdle 30 to prevent the hearth 75 from cracking under the high and uneven temperatures generated by the combustion within the hearth 75. The annular flange 81 also serves as a support for the structure connecting the hearth 75 to the side walls of 35 the furnace or firebox in which the apparatus is installed. The outer wall 82 of the hearth 75 is surrounded by an insulating layer 83 of asbestos or other fire resisting material. The insulating layer 83 prevents the escape and loss of heat by 40 conduction through the hearth 75, thereby conserving fuel.

The modification shown in Figure 6 is generally similar to the preferred form shown in Figure 1 except that the intake portion 112 of the air supply conduit 111 is offset relatively to the spray nozzle 113, so that the air duct 116 is substantially straight and the air duct 115 is approximately in the form of a letter J. In the principal form of the invention (Figure 1), the air duct 15 is approximately in the form of a question mark, (?), due to the substantial alignment of the intake portion 12 with the spray nozzle 13. The remaining features of the modification of Figure 6 are substantially the same as those of the form shown in Figure 1 and are similarly designated by reference numerals.

In the operation of the invention, the vestibule 24 is connected to the conduit from the blower associated with the usual power plant (not shown) and a stream of air supplied thereto. The air enters the vestibule 24 and is divided by the partition or vane 14 into two streams. One stream passes through the duct 16 directly into the air mixing chamber by way of the discharge opening 33, whereas the other stream passes through the air duct 15 along a path shaped substantially like a question mark or sickle and enters the air mixing chamber 18 through the intake opening 19 on the opposite side thereof. The end portions 17 and 22 serve as baffles to prevent the two air streams from colliding abruptly and causes them to blend evenly so as to eliminate dead air spots and insure even combustion in the hearth 75.

The liquid fuel such as fuel oil, is supplied

through the pipe 44 to the spray nozzle 13 and ignited by a spark passing between the electrode ends 60 (Figure 1). The adjusting ring 48 is turned relatively to the auxiliary air tube 46 so that a proper amount of air passes through the ports 47 and 49. Meanwhile, the proportionate amounts of air passing through the ducts 15 and 16 have been adjusted by changing the position of the dampers 25 and 26 by means of the thumb screws 30 and 31 (Figure 1) so that the correct air mixture is obtained in the hearth 75 without dead air spots or areas. The air passing upward from the outlet 71 through the circle 24 shoots outward over the flat zone 76 before encountering the curved inner wall 79 of the hearth 75, thereby providing a cushion of air in the vicinity of the zone 76 and lower portions of the hearth 75. By this means, combustion takes place largely in the upper portions of the hearth 75 so that the lower portions thereof are relatively cool. This construction enables a metallic hearth to be employed, for example cast iron, thereby eliminating the fragility of hearths of refractory materials, such as fire clay. The latter are difficult to ship without breakage and also frequently fail during use, the resulting cracks admitting air and interfering with satisfactory combustion.

While I have shown and described my invention in detail, it is to be understood that the same is to be limited only by the appended claims, for many changes may be made without departing from the spirit and scope of my invention.

What I claim is:

1. In a liquid fuel burner, a casing having therein an air chamber with an outlet, a liquid fuel spray nozzle mounted in said chamber and directed toward the outlet thereof, an air supply conduit connected to said chamber, said conduit having an internal longitudinal partition therein dividing said conduit into outer and inner air supply ducts, said ducts discharging into said chamber at locations remote from each other and on opposite sides of said outlet and means in said conduit for constricting the flow of air through one of said ducts whereby to proportion the air passing through said ducts into said chamber.

2. In a liquid fuel burner, a casing having therein an air chamber with an outlet, a liquid fuel spray nozzle mounted in said chamber and directed toward the outlet thereof, an air supply conduit connected to said chamber, said conduit having an internal longitudinal partition therein dividing said conduit into outer and inner air supply ducts, one of said ducts extending around said chamber and said ducts discharging into said chamber at locations remote from each other and on opposite sides of said outlet and means in said conduit for constricting the flow of air through one of said ducts whereby to proportion the air passing through said ducts into said chamber.

3. In a liquid fuel burner, a casing having therein an air chamber with an outlet, a liquid fuel spray nozzle mounted in said chamber and directed toward the outlet thereof, an air supply conduit connected to said chamber, said conduit having an internal longitudinal partition therein dividing said conduit into outer and inner air supply ducts, said ducts discharging into said chamber at locations remote from each other and on opposite sides of said outlet, and a damper in one of said air ducts arranged to constrict the flow of air therethrough for proportioning the distribution of the air between said ducts.

4. In a liquid fuel burner, a casing having therein an air chamber with an outlet, a liquid fuel spray nozzle mounted in said chamber and directed toward the outlet thereof, an air supply conduit connected to said chamber, said conduit having an internal longitudinal partition therein dividing said conduit into outer and inner air supply ducts, said ducts discharging into said chamber at locations remote from each other and on opposite sides of said outlet, and a damper in each of said air ducts for varying the cross-sectional area thereof whereby to vary the proportionate amounts of air distributed by said ducts to said chamber.

5. In a liquid fuel burner, a casing having therein an air chamber with an outlet, a liquid fuel spray nozzle mounted in said chamber and directed toward the outlet thereof, an air supply conduit connected to said chamber, said conduit having an internal longitudinal partition therein dividing said conduit into outer and inner air supply ducts, said ducts discharging into said chamber at locations remote from each other and on opposite sides of said outlet, and an inwardly-directed baffle at the end of said partition whereby to prevent direct collision between and evenly blend the air streams discharged from said outer and inner ducts into said chamber.

6. In a liquid fuel burner, a casing having therein an air chamber with an outlet, a liquid fuel spray nozzle mounted in said chamber and directed toward the outlet thereof, an air supply conduit connected to said chamber, said conduit having an internal longitudinal partition therein dividing said conduit into outer and inner air supply ducts, said ducts discharging into said chamber at locations remote from each other and on opposite sides of said outlet, and an inwardly-directed baffle at the end of said partition and a second inwardly-directed baffle at the location of entry of said inner air duct into said chamber whereby to prevent direct collision between and evenly blend the air streams discharged from said outer and inner ducts into said chamber.

7. In a liquid fuel burner, a casing having therein an air chamber with an outlet, a liquid fuel spray nozzle mounted in said chamber and directed toward the outlet thereof, and an air supply conduit assembly connected to said chamber, said conduit assembly having a plurality of air supply ducts discharging into said chamber at remotely separated locations on opposite sides of said outlet, one of said ducts being approximately sickle-shaped and partially encircling said chamber.

8. In a liquid fuel burner, a casing having therein an air chamber with an outlet, a liquid fuel spray nozzle mounted in said chamber and directed toward the outlet thereof, an air supply conduit assembly connected to said chamber, said conduit assembly having a plurality of air supply ducts discharging into said chamber at remotely separated locations on opposite sides of said outlet, one of said ducts being approximately sickle-shaped and partially encircling said chamber, and air proportioning mechanism extending into said ducts for varying the proportionate amounts of air distributed by said ducts to said chamber.

9. An air supply casing for fuel burners comprising a housing having therein an air chamber with an outlet, and an air supply conduit connected to said chamber, said conduit having an internal longitudinal partition therein dividing

said conduit into outer and inner supply ducts, one of said ducts partially encircling said chamber and said ducts discharging into said chamber at locations remote from and on opposite sides of said outlet.

10. An air supply casing for fuel burners comprising a housing having therein an air chamber with an outlet, an air supply conduit connected to said chamber, said conduit having an internal longitudinal partition therein dividing said conduit into outer and inner supply ducts, one of said ducts partially encircling said chamber and said ducts discharging into said chamber at locations remote from and on opposite sides of said outlet, and valve means in said conduit arranged to vary the cross-sectional area of each duct for proportionately distributing the air supplied thereto between said ducts.
